(57) CLAIM

The ornamental design for a makeup shield, as shown and described.

DESCRIPTION

FIG. 1 is a front perspective view of the makeup shield, with a portion of unclaimed environmental structure shown;
FIG. 2 is a front view of the makeup shield, with a portion of unclaimed environmental structure shown;
FIG. 3 is a rear view of the makeup shield, with a portion of unclaimed environmental structure shown;
FIG. 4 is a side view of the makeup shield, with a portion of unclaimed environmental structure shown;
FIG. 5 is a opposite side view of the makeup shield, with a portion of unclaimed environmental structure shown;
FIG. 6 is a top view of the makeup shield, with a portion of unclaimed environmental structure shown; and,
FIG. 7 is bottom view of the makeup shield, with a portion of unclaimed environmental structure shown.
The broken lines shown in the drawings represent environmental structure and/or unclaimed portions of the makeup shield, and form no part of the claimed design.
